PORTABLE ROTATABLE FOOD SERVER

Maurice Joseph Van Horn, Jr., Rte. 2, Box 236,
Church Road, Reisterstown, Md. 21136

Filed June 14, 1966, Ser. No. 2,673

Term of patent 14 years

(Cl. D33—3)

FIG. 1 is a perspective of the portable food server illustrating my design;

FIG. 2, a top plan view thereof;

FIG. 3, a side elevation; and

FIG. 4, a bottom plan view.

The present invention is characterized by a relatively large spherical body with a series of generally flat rings having a diameter which is smaller than the diameter of the body and such rings are mounted around the periphery of the body. The spherical body is mounted on an upright post having a handle forming ring at one end and a tripod type stand at the opposite end.

I claim:

The ornamental design for portable rotatable food server, as shown and described.
